(57) **CLAIM**

What is claimed is the ornamental design for smoker's accessory, as shown and described.

DESCRIPTION

FIG. 1 is a front perspective view of the smoker's accessory according to the present invention;

FIG. 2 is a back perspective view of the smoker's accessory according to the present invention;

FIG. 3 is a front view of the smoker's accessory according to the present invention;

FIG. 4 is a back view of the smoker's accessory according to the present invention;

FIG. 5 is a right side view of the smoker's accessory according to the present invention;

FIG. 6 is a left side view of the smoker's accessory according to the present invention;

FIG. 7 is a top view of the smoker's accessory; and,

FIG. 8 is a bottom view of the smoker's accessory.

The smoker's accessory is shown with a symbolic break in its length in FIGS. 1–6. The appearance of any portion of the article between the break lines forms no part of the claimed design. All other broken lines in the drawings depict portions of the smoker's accessory that form no part of the claimed design.
